ELECTRICAL SWITCH

Jerome S. Linn, Los Angeles, Calif., assignor to
 Elcon Mfg. Co., Los Angeles, Calif., a corpora-
 tion of California

Application January 31, 1949, Serial No. 73,727

3 Claims. (Cl. 200—68)

1

This invention relates generally to improved electric switches having novel structural characteristics rendering them especially desirable for use in aircraft and under other similarly exacting conditions.

A major object of the invention is to provide a switch relatively smaller and more compact than other switches of corresponding capacity and effectiveness. For this reason, I employ a novel spring arrangement especially designed to act both as a contact shifting member and as a means for urging the contacts into tight engagement in circuit closing position. Preferably, the spring takes a double bowed form, a movable contact being carried by the spring intermediate its two bowed ends.

It is a further object of the invention to provide an extremely simple switch having a movable contact adapted to snap suddenly from one position to another irrespective of the rate at which the control element or handle is actuated. To effect this purpose, I employ stationary and movable contacts having inter-engaging irregularities acting to releasably retain the movable contact against displacement during the first part of a shifting movement and until enough energy has been stored in a shifting spring to result in the defined snap action. The movable contact may be cylindrical in form and receivable within a partial cylindrical recess in one or more stationary contacts.

I also provide a novel member adapted to assure shifting of the movable contact upon movement of the control element if the spring fails to cause such displacement. This member may be U-shaped to straddle a central hub of the movable contact and displace that hub by movement in either direction.

The invention affords a unique type of contact movement resulting in effective wiping of the contact surfaces during the first period of handle movement in any direction and before the movable contact commences its travel away from the stationary contact. This novel wiping action results from slight rotation of a cylindrical contact within an engaging cylindrical recess in another contact, and is caused by the novel spring drive. To maximize the wiping rotation, I preferably employ an additional spring or strap loosely carried by a main double bowed spring and movable relative to that bowed spring during the first stages of shifting motion.

The present invention may be embodied in a sustained contact switch or in a momentary contact switch, that is, one in which the movable

2

parts return to a normal position as soon as the control element or handle is released. Novel yielding means are used if such momentary contact is desired, these means preferably comprising an H-shaped overriding spring bearing against the switch body to urge the movable contact to normal position.

It is often desirable, where widely varied environmental conditions are to be encountered, to hermetically seal the outer case of a switch in order to protect its mechanism against injury from the environment. In the present invention, I employ means for effecting such sealing while permitting complete freedom of motion of the operating handle or lever and the other moving parts. For this purpose, I disclose a flexible sealing element to be secured about a control element and to the switch housing about the periphery of an opening through which the control element passes. In accordance with the invention, the sealing element may take the form of a flexible annular diaphragm which is desirably retained at its inner edge between a pair of hemispherical sections serving together as a toggle ball. It is contemplated that the diaphragm will take an optimum form having such shape and material distribution as to minimize stress in all positions of the handle or control element.

The above and further features and objects of the present invention will be better understood from the following detailed description of the typical embodiment illustrated in the accompanying drawings, in which:

Fig. 1 is a side view of the switch with its side wall broken away and with a portion of the base broken away to disclose three of the stationary contacts;

Fig. 2 is a transverse section taken on line 2—2 of Fig. 1 and showing one portion of the movable contact in section and the other portion in elevation;

Fig. 3 is a section taken on line 3—3 of Fig. 2;

Fig. 4 is a section taken on line 4—4 of Fig. 3;

Fig. 5 is an enlarged fragmentary section taken on line 5—5 of Fig. 2;

Fig. 6 is an enlarged fragmentary section showing the sealing diaphragm and its means of attachment to the switch case and operating mechanism;

Fig. 7 is a schematic representation of the movable contact and a stationary contact showing, in exaggerated form, their different radii of curvature;

Fig. 8 is an enlarged elevation of the diaphragm;

Fig. 9 is a graphical representation of the optimum circumferential contour of the diaphragm; and

Fig. 10 is a perspective view of one corner of the switch base.

The single pole 3-position switch represented in the drawings comprises essentially a substantially rectangular case 10, a contact and terminal carrying base 11, and movable control mechanism, generally indicated at 12. The case is open at its lower side as seen in Figs. 1 through 3, to provide an opening for reception of the base. Upper wall 73 of the case carries face plate 13 suitably secured to the case as by spot welding at 14 and 15. The upper wall of the case and end plate 13 have corresponding elongated openings or slots 16 and 17 extending longitudinally of the switch, and are deformed in opposite directions about those openings to form angularly disposed annular portions 19 and 20 which provide space for the reception of diaphragm 18 and serve as retaining means for the movable mechanism later to be described. The upper surface of the case is downwardly offset from the plate outwardly of portions 19 and 20 to form a narrow annular space 21 between the plate and case and within which the periphery of the diaphragm is clamped. The opposed surfaces of plate 13 and the upper wall of the case are notched at 22 within space 21 to assure a positive seal and prevent displacement of the diaphragm. The diaphragm is annular in configuration, as seen in Fig. 8, and is retained inwardly by the movable mechanism in a manner later to be described. Openings 23 and 24 in the face plate permit mounting of the switch on a control panel or other support.

Base 11 is molded of suitable insulating material, preferably high strength asbestos filled plastic. The base presents an angularly disposed outwardly facing wedge surface 24 of essentially rectangular horizontal section and adapted to be forced into the open lower end of case 10 against the inner surface of its side walls 27 to maintain the case and base in assembled relation and to provide a fluid tight seal between them. This seal may be augmented by the application of a bonding cement before forcing the two parts together. Peripheral flange 25 on the base engages the lower surface 26 of the case side walls 27 with the base in assembled position. As seen in Fig. 10, each of the four corners of the base has a recess 95 at its point of engagement with the case into which the adjacent portion of the case is peened to further assure retention of the two parts in correct assembled relation.

The various stationary contacts and terminals are molded into the base during its formation. At one side of the longitudinal center line designated by section line 3—3 in Fig. 2, three stationary contacts 23, 29 and 30 are accurately disposed in upwardly facing positions (see Fig. 1). Each of these contacts presents a partial cylindrical upper contact surface 90 engageable by a cylindrical movable contact later to be described. The base itself presents non-conducting surfaces 31 between the adjacent contacts of the above three and beyond the end ones to form, with the contacts, a more or less continuous accurate surface having a slight recess at each contact. Terminals 32, 33 and 34 extend upwardly through the base to electrically engage contacts 23, 29, and 30, respectively. At their lower exposed ends, these terminals present

threaded openings 35, 36 and 37, within which screws 38, 39 and 40, each carrying a washer 41, are threadedly received.

At the other side of the longitudinal center line, a single terminal 42 electrically engages three stationary contacts 43, 44 and 45, corresponding in configuration and location to contacts 28, 29 and 30 (see Figs. 3 and 5). Thus, the upper partial cylindrical surfaces 90 of contacts 28 and 43 are in alignment. Similarly, the upper surfaces of contacts 29 and 44 and of contacts 30 and 45 are in alignment to permit cylindrical movable contact 77, later to be described, to bridge them. On its lower surface, terminal 42 presents opening 46, within which screw 47, carrying washer 48, is threadedly received.

Thin insulating spacer 49 is molded into the base during its formation in depending relation to the base, and extends longitudinally along its center line between the lower portions of terminals 32, 33 and 34 on one side, and terminal 42 on the other side to prevent any direct electrical connection between these terminals. At the top of the base, insulating guide 50 having a bottom 92 and a pair of U-shaped side walls 93, is retained in upstanding position between contacts 28, 29 and 30 and the upper ends of their associated terminals at one side, and contacts 43, 44 and 45 and terminal 42. The plastic base is recessed at 51 for the reception of guide 50. At each end beyond the stationary contacts, the base presents a pair of substantially horizontal upwardly facing shoulders 52, one to either side of guide 50.

As shown in exaggerated form in Fig. 7, the common radius of curvature of the partial cylindrical surfaces 90 on the faces of the outer surfaces of the stationary contacts is somewhat larger than that of the outer surfaces of the movable contact, in order to assure satisfactory electrical engagement. The dashed line of Fig. 7 represents the curvature of the surfaces 90 on the stationary contacts.

Movable mechanism 12 is built up around pin 53, which extends upwardly through openings 16 and 17 in the case and face plate. The lower end of this pin is knurled at 54 and molded within opening 55 in U-shaped positive action yoke 56, which is formed of suitable plastic or other insulating material. Yoke 56 presents an outwardly facing substantially cylindrical surface 57 adjacent its upper surface 58. As best seen in Fig. 4, surface 57 has a pair of diametrically opposed straight portions 59 directed toward the ends of the switch. Two leaf type springs 60 and 61 have upper enlarged circular portions 62 and 63, respectively, with openings of size and shape corresponding to the sectional configuration of surface 57 and are receivable about that surface. Washer 64 has a similar opening and is received about surface 57 above the springs. As will be understood, engagement of the non-cylindrical portions 59 of surface 57 with the openings of springs 60 and 61 and washer 64 serves to key the springs in the illustrated positions relative to yoke 56.

Insulating washer 65 is received about pin 53 above yoke 56 to engage its upper surface 58 and washer 64. Such engagement of washer 64 serves to rigidly retain the two springs against displacement from the yoke. Toggle ball sections 66 and 67, have openings 96 and 97 of internal diameters corresponding to the external diameter of the pin, are received about the pin above washer 65. Handle 68 is threaded onto the upper end of the pin at 69 to urge all of the parts car-

ried by the pin downwardly against yoke 56 and thus form a single movable unit including the handle, pin, ball sections, washer, yoke, and springs 60 and 61. Upper ball section 67 has a slightly enlarged internal diameter at 71 extending upwardly from its bottom to form an annular recess within which the inner portion of the diaphragm is clamped to form a first fluid tight seal. The next adjacent outer portion of the seal is clamped between the opposed horizontal surfaces of the two ball sections to afford a second fluid seal. The ball sections present complementary outer partial spherical surfaces 94 engageable with the inner partial spherical surfaces 72 of plate 13 and upper wall 73 of the case. Such mounting of the movable mechanism, that is by engagement of the ball sections with surfaces 72, permits pivotal movement of handle 68 between the central full line position of Fig. 1 and the two positions illustrated in dot-dash lines.

Spring 60 presents a bowed portion 73 at either end, and is preloaded in the position of Fig. 3 to urge the free hooked ends 74 downwardly. U-shaped strap or spring 75 has similarly hooked ends 76 loosely engaging ends 74 of spring 60, and is thus urged downwardly also. Both spring 69 and strap 75 are of such width as to permit the reception of their lower portions between walls 93 of guide 59, which thus serve to insulate the springs from the stationary contacts and terminals (see Figs. 2 and 4).

Movable contact 77 is carried, at its central hub portion 78, by strap 75. At each side of this hub portion, contact 77 has an enlarged diameter portion 79, carrying a cylindrical contacting portion 80. As will be understood, the movable contact is displaceable between three positions of bridging engagement with the various stationary contacts. For instance, in the central position shown in the drawings, the two cylindrical portions 80 of the movable contact engage the central stationary contacts 29 and 44 to close a circuit between these two contacts through hub portion 78. Similarly, the movable contact may be displaced to a position of bridging engagement with contacts 28 and 43 or contacts 30 and 45. Pivotal movement of handle 68 serves to effect such displacement through double spring 60.

If it is desired that the switch be of the sustained contact type, overriding spring 61 need not be employed. That spring is to be used only in case the switch is intended to be of the momentary action type, in which the central position is the normal one, and the switch automatically returns to that position after release of the handle. Spring 61 is substantially H-shaped (see Fig. 4) with the previously referred to portion 63 forming its cross piece, and presents downwardly curved outer extremities or legs 81 straddling spring 60 and insulating guide 59 and engageable with the four upper surfaces 52 of the base. Any movement of handle 68 resiliently deforms the two legs of spring 61 at one end of the switch and moves the legs at the other end upwardly against the top wall of the case in a manner such that all four of the legs act together to urge the switch toward its normal central position.

From the foregoing description, it will be evident that spring 60 carries out the dual functions of urging the movable contact into tight engagement with the stationary contacts in any of the three positions of the switch, and serving as a contact displacing or drive member. During the initial stages of handle movement between

any two of the three positions shown in Fig. 1, engagement of the cylindrical movable contact with two corresponding stationary contacts prevents immediate displacement of the movable contact and stores energy within spring 60 as a result of its deformation by the handle. At a predetermined stage in the handle movement, the energy stored within the spring is sufficient to overcome the detent action of the contacts and effect a sudden snap movement of the movable contact between positions. Such snap action minimizes sparking and resultant contact deterioration. If, for any cause, the movable contact is not displaced by spring 60, one of the inner surfaces 82 of element 56 engages strap 75 to positively displace the movable contact in the desired direction. Spring 61 urges the handle and associated movable parts toward the centered position at all times, and returns the switch to this normal condition when the handle is released.

Because of the novel construction of spring 60 and its loose connection with strap 75 through hooked ends 74 and 76, movement of the handle causes rotation of the movable contact before it is laterally displaced. This rotation results in an effective contact wiping action which clears the surfaces of the contacts in response to each switch operation. Specifically, movement of the handle tends to lower one side of spring 60 and thus pivot strap 75 about the axis of the movable contact, and in turn to rotate that contact. An additional wiping action results from the lateral displacement of the movable contact off of the stationary contact during its snap movement between positions.

Leads from the circuits to be controlled are secured to terminals 32, 33, 34 and 42 by the terminal screws. The switch normally closes the circuit between terminals 33 and 42 but breaks that circuit and temporarily closes another between terminals 32 and 42 or 34 and 42 when the handle is actuated to one of the dot-dash positions. Though I have described the invention as embodied in a three "on" position single pole switch, its novel aspects may obviously be incorporated in switches with other contact arrangements.

Since diaphragm 18 must be deformed upon each movement of the switch, I form that diaphragm with such predetermined material distribution and shape characteristics as to minimize the stress to which it will be subjected and consequently lengthen its active life. It is intended that, for any switch embodying the invention, the optimum size and shape will be calculated in accordance with known mathematical methods which need not be discussed in detail here. I have calculated the most desirable arrangement for a circular diaphragm of the type shown in the drawings with a handle throw (angle α of Fig. 1) of 25 degrees, and will briefly note the results.

The material distribution in the diaphragm must be such as to induce minimum stresses and good stress distribution with the handle in the center or either of the thrown positions. The shape and material distribution for optimum stress conditions with the handle centered differs from the shape and material distribution for optimum stress conditions with the switch thrown. The difference in these ideal material distributions is a function of the ratio of the inside clamping diameter B (see Fig. 8) to the outside clamping diameter C. As the inside diam-

eter becomes small and the ratio approaches zero, the material distribution difference approaches zero.

The optimum material distribution can be described by reference to two contours, a radial contour and a circumferential contour. The radial contour is most appropriately taken along the line of action of handle 68, that is, along line 83 of Fig. 8, and is represented in enlarged section by Fig. 6. The circumferential contour is best taken at approximately the middle of the unclamped diaphragm area, i. e., along line 84 of Fig. 8.

The optimum radial contour along the line of action with the switch in one of the thrown positions, that is with the handle in a dot-dash position of Fig. 1 or Fig. 6, takes the form of a sine function slightly greater than 270 degrees in length and is represented by curve 85 of Fig. 6. The ideal shape in the centered position would, of course, be a flat disc, in which case the radial and circumferential contours would both be straight lines. The ideal unclamped length of material along the line of action to prevent excessive stress in any of the three positions is intermediate the amount required to permit the assumption of a 270 degree sine shape in thrown position and that required to form a flat disc in centered position. The most desirable value is approximately the mean of these two, and takes the full line form of Fig. 6 in center position and the dot-dash shape in thrown position.

The ideal circumferential contour in thrown position takes the approximate form of a cosine curve with reverse curvature, starting from the line of action, and is represented by curve 86 in the graph of Fig. 9, being the radial angle taken from the line of action 83 in Fig. 8. The optimum circumferential contour for a diaphragm in centered position, assuming the use of a shape other than a flat disc and assuming that the diaphragm will extend in substantially a straight line from side to side, that is along line 87 of Fig. 8, is a 90 degree cosine function, represented by curve 88 of Fig. 9. The optimum circumferential contour is approximately the mean of these two curves, or curve 89 of Fig. 9.

I claim:

1. A switch comprising a movable operating element, a spring having a pair of oppositely bowed portions carried by said element for movement thereby, said portions terminating outwardly in oppositely disposed free ends, a member loosely carried by and between said free ends of the spring, a stationary contact and a movable contact carried by said member and urged by the tension of said bowed spring portions into engagement with said stationary contact in one position of the switch, one of said contacts having a recess within which the other contact is partially receivable in said position of the switch to releasably retain said movable contact against relative lateral displacement, whereby movement of said operating element tending to laterally displace said movable contact effects initial distortion of said bowed portions of the spring followed by sudden movement of said movable contact from engagement with said stationary contact.

2. A switch comprising a movable operating element, a spring having a pair of oppositely bowed portions carried by said element for movement thereby, said portions terminating outwardly in oppositely disposed free ends, a substantially U-shaped yoke carried by and between said free ends of the spring, a stationary contact and a movable contact carried by said yoke and urged by the tension of said bowed spring portions into engagement with said stationary contact in one position of the switch, one of said contacts having a recess within which the other contact is partially receivable in said position of the switch to releasably retain said movable contact against relative lateral displacement, whereby movement of said operating element tending to laterally displace said movable contact effects initial distortion of said bowed portions of the spring followed by sudden movement of said movable contact from engagement with said stationary contact.

3. A switch comprising a movable operating element, a spring having a pair of oppositely bowed portions carried by said element for movement thereby, said portions terminating outwardly in oppositely disposed free ends, a substantially U-shaped yoke carried by and between said free ends of the spring, a stationary contact, and a movable contact carried by said yoke and urged by the tension of said bowed spring portions into engagement with said stationary contact in one position of the switch, one of said contacts having a recess within which the other contact is partially receivable in said position of the switch to releasably retain said movable contact against relative lateral displacement, whereby movement of said operating element tending to laterally displace said movable contact effects initial distortion of said bowed portions of the spring followed by sudden movement of said movable contact from engagement with said stationary contact, said free ends of the spring and said U-shaped yoke being connected by loosely interengaged and relatively movable hooked portions.
